PILOT FOR VAPORIZING BURNERS

Carl S. Greer, Jr., Albion, Mich., assignor to
Loneragan Manufacturing Company, Albion,
Mich., a corporation of Michigan

Application October 28, 1948, Serial No. 57,095

2 Claims. (Cl. 158—91)

1

This invention relates to a vaporizing pot type burner for liquid fuel and has for an object the provision of an improved form of vaporization chamber in the vaporizing pot.

Burners of the vaporizing pot type usually comprise a pot having a plurality of primary and secondary air inlet openings in the side walls and a centrally apertured baffle dividing the pot into a lower vaporizing chamber and an upper vaporizing chamber. The principal problem encountered in burners of this type lies in producing a clean and stable fire at all stages of operation. It is found that dividing the pot into lower and upper vaporizing chambers does not permit a low turndown of the fuel supply to a pilot fire. Eddy currents form in the lower chamber below the partition and either cause a smoky, sooty fire or at times permit the fire to be completely extinguished. Anything lower than an intermediate fire gives trouble, and consequently, necessitates burning a higher flame than necessary and the generation of excessive heat. Not only is there unnecessary waste, but an uncomfortable condition is created in the room. This problem has been effectively solved by the provision of opposing segments at or near the floor of the pot defining laterally confined areas with a space between the segments which acts as a mixing and combustion chamber beginning at the floor at low fire and extending to the flame opening at the top of the pot at high fire.

An object of this invention is to provide an improved form of vaporizing chamber for said opposing segments which is exceptionally efficient and which will provide a pilot flame for the vaporizing pot in addition to the low flame beginning at the floor of the pot in the space between said segments.

A further object of the invention is to incorporate this vaporizing chamber in one of said segments whereby a simple structure is provided without additional parts which are apt to affect the efficiency of the pilot flame or the flame at low or high fire.

Other objects and advantages of the invention will be apparent from the following detailed description when taken in connection with the drawings which form a part hereof.

In the drawings:

Figure 1 is a cross-sectional view of an oil burner embodying the present invention;

Fig. 2 is a top view in elevation of the vaporizing pot;

Fig. 3 is a cross-sectional view taken on line 3—3 of Fig. 2 looking in the direction of the arrows; and

2

Fig. 4 is a similar view but taken on line 4—4 of Fig. 2 looking in the direction of the arrows.

The heater illustrated in the drawings is what is commonly called a space heater. It will be understood, however, that this heater may be of any other type and that the invention may be incorporated in central heating units, furnaces generally, stoves, etc. As illustrated, the heater comprises a housing 1, a supporting frame 2, a combustion chamber 3 and a burner chamber 4. This burner chamber 4 is disposed in pot 5 supported in any suitable way in housing 1, this depending upon the design of the housing and the type of heater in which this pot 5 is used. The shape of pot 5 will also depend upon the shape and type of the heater. It is illustrated as elliptical or oval and has a side wall 6 provided with uniformly spaced groups of air inlet openings. These groups of air inlet openings are disposed at different levels, the primary air inlet openings 7 being located in rows below the secondary air inlet openings 8. If the side wall 6 is sheet metal, these air inlet openings may be formed therein before the wall is formed, but, irrespective of how the wall is formed, they may be of substantially uniform size and spacing. The bottom 9 of pot 5 may be a cast metal or sheet metal pan with a well 10 substantially centrally provided and a trough 11 leading thereto from one side of the pot. As illustrated, oil line 12 will connect at 13 to supply oil at a controlled rate to trough 11 by a suitable metering device 14. The upper wall of pot 5 rests on side wall 6 and is in the form of an apertured flame plate 15 with a flame opening 17 and an annular depending flange 16 holding the plate in position.

Two accumulator segments or elements 20 and 21 are provided in burner chamber 4 and are arranged to embrace a number of primary air inlet openings 7, and, while only those of the lower row are illustrated as included, it will be understood that openings of other rows might also be included. Accumulator elements 20 and 21 are specifically shown as substantially U-shaped, each with a top wall 22 and with side walls, and are seated preferably upon bottom 9 in opposing relation against the side wall 6 of pot 5. The inside edges of these top and side walls of the accumulator elements may be cut somewhat arcuate to conform to the shape of side wall 6 of the pot.

Accumulator segment 21 has side walls 23 and 24 extending substantially parallel to each other and inwardly from side wall 6 of pot 5. Accumulator segment 20 has one of its walls 25 constructed in the same manner, but, at the opposite side,

its side wall 26 extends at an acute angle toward the major axis or center line of the pot. This side wall 26 is greater in length than side walls 23, 24 and 25, and almost reaches the major axis of the pot, the front edge thereof being considerably closer therefore to this center line of the pot than the front edges of side walls 23, 24 and 25. Top wall 22 also extends the same distance toward this center line at 27 and integrally joins side wall 26 to provide a forwardly projecting or pocket-like enclosed area 28. Trough 11 runs parallel to side wall 26 and lies in this enclosed area 28. Enclosed area 28 effectively forms a simple vaporizing chamber defined only by a side wall and a limited portion of the top wall of one of the segments. No added parts are required other than an extended side wall and top wall capable of turning the pilot flame at an angle to burn in the direction of the center of pot 5. It will be noted that additional air openings 29 have been furnished in the side wall 6 of pot 5 to provide the necessary volume of air to assure a proper mixture at pilot flame with minimum fuel consumption at this stage without formation of smoke or carbon.

The supply of liquid fuel to the burner chamber 4 may be controlled by suitable adjustment of the metering device 14. The liquid fuel entering at 13 will vaporize and form a combustible mixture and burn at low or pilot flame at and slightly to the rear of the forward edge of the top wall 22 at the extended portion 27 of vaporizing chamber 28. At this stage of operation, a minimum consumption of oil takes place, and, in actual operation, it is found that the arrangement of the parts provides for a consumption as low as 1 cc. of oil per minute without smoke or carbon being produced. The flame may continue to burn at a low pilot stage indefinitely with a clear, smokeless appearance, and the mixture will be adequate to effect complete combustion. By increasing the supply of liquid fuel, the pilot flame will increase until the flame either is held at intermediate stage, which is within the zone defined by the space between the accumulator elements 20 and 21 and in the vicinity of their top walls 22, or is permitted to rise in burner chamber 4 until it burns at and above opening 17 in flame plate 15 where combustion is then completed in combustion chamber 3 at high fire stage.

Accumulator elements 20 and 21 serve to direct the air entering the lower primary air inlet openings 7 embraced by these elements to the space therebetween to mix with the vaporized oil rising from well 10. The combustible mixture at intermediate fire will burn in this space slightly above or at the level of top walls 22 and consume at this stage, say, between 6 and 8 cc. of liquid fuel per minute, without the flame smoking or producing carbon. Accumulator elements 20 and 21 will direct a somewhat uniform flow of air forward and prevent undesirable eddy currents. As the fuel supply increases, the level of the flame will increase so that the air supplied by the upper primary air inlets 7 will mix with the vaporized fuel to provide a completely combustible mixture. With the flame at opening 17 and burning in combustion chamber 3, the secondary air inlets 8 will supply additional air to the mixture and assure complete combustion, the flame at this high stage consuming between 35 and 45 cc. of liquid fuel per minute.

It is not necessary to go from pilot flame to intermediate stage. Merely increasing the supply of

liquid fuel slightly will increase the pilot flame during mild weather when little heat is desirable. The burner may operate economically at minimum flame to generate the heat necessary for the room without being compelled to generate excessive heat by the use of a larger flame and thus cause unnecessary waste. The ease of controlling minimum flame and of controlling oil consumption from this exceptionally low pilot to an intermediate stage without requiring the intermediate stage as a starting flame to avoid smoke and carbon, are obviously the result of the arrangement of the parts including the elements 20 and 21 and the vaporizing chamber 28 forming a part of the element 20.

The pot 5 and its accumulator elements, together with the simple form of vaporizing chamber 28 disclosed, may obviously be incorporated in any burner whether in a space heater, stove or furnace. These parts may be proportioned to provide a burner of a desirable capacity that will burn liquid fuel economically and with minimum fuel consumption.

The vaporizing chamber 28 is simple and is easy to form. As previously stated, additional parts heretofore found necessary to form a vaporizing chamber in a vaporizing pot have been eliminated. The simple pilot structure is brought about by the advantageous form of the accumulator segments whereby the top wall 22 of one of the accumulator segments may be extended far enough about the inner periphery of pot 5 so that there will be provided a resulting side wall 26 of a length that will form a vaporizing chamber of adequate proportions permitting adequate vaporization and proper mixture capable of being burned at pilot stage without smoke and carbon. The pilot flame may be increased from an extremely low stage by varying degrees until the intermediate flame stage is reached without the flame smoking or without producing carbon or soot. During this period of increasing pilot flame, the accumulator elements supply enough air to effect complete combustion of the mixture produced and hold the generation of vapor to the vicinity of well 10. In this manner, control at low flame stages may be had to prevent fluttering and a consequent incomplete burning that would otherwise produce smoke and carbon.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. A liquid fuel burner comprising, in combination, a combustion pot of elongated cross section and having a bottom wall, a side wall and an apertured flame plate at the top of said side wall, a plurality of spaced air inlet openings disposed circumferentially about said side wall, segments disposed adjacent said bottom wall and extending upwardly therefrom along a portion of said side wall and spaced on opposite sides of the longitudinal axis of said pot and about the air inlet openings disposed in said portions, said segments having opposed side walls substantially at their ends and a top wall extending from one side wall to the other side wall, one of said side walls of one of said segments being turned inwardly to-

ward the vertical central axis of the pot and toward the longitudinal axis of said pot and extended close to said longitudinal axis, said segment's top wall being curved at said one end also toward said longitudinal axis to meet the inner edge of said turned side wall, and means to deliver a regulatable quantity of fuel to said pot bottom adjacent to said one side wall and within the last said segment.

2. A liquid fuel burner comprising, in combination, a combustion pot of elongated cross section and having a bottom wall, a side wall and an apertured flame plate at the top of said side wall, a plurality of spaced air inlet openings disposed circumferentially about said side wall, segments disposed against said bottom wall and extending upwardly therefrom along a portion of said side wall and spaced on opposite sides of the longitudinal axis of said pot and about the air inlet openings disposed in said portions, said segments having opposed side walls substantially at their ends and a top wall extending substantially from one side wall to the other side wall, said side walls acting as the feet of said one segment to support the latter resting upon said bottom wall of said pot, one of said side walls of one of said segments being formed at an angle with respect

to the other side wall and turned inwardly toward the vertical central axis of the pot and having its inner edge closer to the longitudinal axis of said pot than the inner edge of the other side wall and extended close to said longitudinal axis, said segment's top wall being curved at said one end also toward said longitudinal axis to meet the inner edge of said turned side wall, a trough in said bottom wall within said one segment but adjacent to said angularly formed side wall, and means for supplying a regulatable quantity of fuel to said trough.
